(57) **CLAIM**

The ornamental design for a ratchet gear for a seat belt adjuster as shown and described.

DESCRIPTION

FIG. 1 is a perspective view of a ratchet gear for a seat belt adjuster showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a fragmentary cross-sectional view taken along line 8-8 in FIG. 2;

FIG. 9 is a perspective view of the design in a state of use with broken line environment;

FIG. 10 is a perspective view of the design in another state of use with broken line environment; and,

FIG. 11 is a perspective view of the design in still another state of use with broken line environment.

The dashed broken lines are for illustrating environment structure only and form no part of the claimed design.

The broken lines crossing over the article in FIG. 2, are included for the purpose of illustrating the sources of the sectional views and from no part of the claimed design.
